UNITED STATES PATENT OFFICE.

HAROLD P. TIPPETT, OF COLUMBUS, OHIO, ASSIGNOR TO THE N. L. HAYDEN COMPANY, OF COLUMBUS, OHIO, A CORPORATION OF OHIO.

METALLIC PACKING.

SPECIFICATION forming part of Letters Patent No. 770,483, dated September 20, 1904.

Application filed July 8, 1904. Serial No. 215,698. (No model.)

To all whom it may concern:

Be it known that I, HAROLD P. TIPPETT, a citizen of the United States, residing at Columbus, in the county of Franklin and State of Ohio, have invented a certain new and useful Improvement in Metallic Packings, of which the following is a specification.

My invention relates to a new and useful improvement in metallic packings.

10 The object of the invention is to provide a packing in which certain difficulties heretofore encountered are overcome. In such packings where segments that interlock have been employed it has been found necessary to force 15 said segments into their locking engagement around the rod, and when once they are locked together it is impossible to remove them without breaking the lips or entirely disengaging the segments from the rod. Packings of this 20 nature wear more rapidly upon their sides than upon their inner or outer peripheries, and where interlocking lips are used the packing soon wears so thin that the lips break off, which greatly decreases the efficiency and life 25 of the packing. Therefore the more essential purposes of my invention are to provide a packing that will obviate the above objection and one which is peculiarly shaped and formed so as to readily fit in place and present steam- 30 tight joints under all pressures.

Finally, the object of the invention is to provide a device of the character described that will be strong, durable, and efficient and comparatively simple and inexpensive to make and 35 one that will be operative throughout its life.

With the above and other objects in view the invention consists of the novel details of construction and operation, a preferable embodiment of which is described in the specification and illustrated in the drawings, wherein—

Figure 1 is a view in elevation of my packing-ring. Fig. 2 is a detailed elevation of one of the segments. Fig. 3 is an inner face view 45 of the segment. Fig. 4 is a plan view of the ring, and Fig. 5 is a detailed end view of the tongue end of the segment.

In the drawings the numeral 1 designates the segments of which the ring is composed.

Ordinarily I employ three of these segments; 50 but where packings of considerable diameter are employed more segments may be used. Each segment is formed with a tongue 2, having the angular end 3 and extending from the angular shoulder 4. The tongue 2 has a width 55 equal to half of that of the segment and extends from the diametrical center of the segment to the outer surface thereof. An inclined face 5, extending in the same plane with the shoulder 4, projects from the side of the 60 tongue 2. The opposite end of the segment is formed with an L-shaped inclined face 6, which conforms and registers with the shoulder 4 and the inclined face 5 of the next adjacent segment when the same are assembled in the ring. An offset recess 7 is formed with an inclined wall 8, which extends at such an angle as to contact and register with the end 3 of the tongue 2 when the shoulder 4 and faces 5 and 6 are brought into 70 contact. It is to be observed that the inclined face 6 and the tongue 2 extend in opposite directions from the diametrical center of the segment and that the recess 7 and inclined face 5 are disposed likewise. It will be readily 75 seen that there are no thin projecting lips to wear and snap off and that the segments when once assembled are held against longitudinal displacement upon the rod. Each segment is formed with slightly-rounded sides 9, which 80 curve inward from the inner periphery or bore 10 to the outer periphery 11, which is, as shown in the drawings, considerably narrower than the said inner periphery. The packing is especially designed to be used in connection 85 with a suitable spring-rigging. It is to be observed that the tongue 2 is quite short and “stubby,” while the recess 7 is comparatively small, thus presenting an extremely strong and durable packing-segment. It is also to 90 be observed that as most of the wear is taken up by the sides 9 the bottom wall 12 of the offset recess 7 practically maintains the same thickness as the said wearing action takes place, thus preserving its efficiency during the 95 entire life of the packing. When the segments are assembled about a rod, the engaging elements register, as hereinbefore described,

and the pressure of the steam will tend to drive the segments into close contact, thus producing a steam-tight joint.

Having now fully described my invention, 5 what I claim, and desire to secure by Letters Patent, is—

1. A metallic packing-ring composed of segments having rounded outer faces, each segment comprising a shouldered inclined face 10 having a tongue projecting therefrom, and an inclined L-shaped face provided with an offset recess having an inclined rear wall adapted to receive the tongue of the next adjacent segment when the segments are assembled.
- 15 2. A metallic packing-ring composed of segments having the curved faces 9 and the inner periphery 10 of greater width than the outer

periphery 11, each segment having the tongue 2 provided with the inclined end 3 projecting from the inclined shoulder 4, and the inclined 20 face 5 extending in a plane parallel to the shoulder 4 which lies at an angle to the end 3, and said segment being formed on its opposite end with the inclined L-shaped face 6 conforming to the angle of the plane of the inclined face 5 and shoulder 4, and an offset recess 7 formed in the face 6 and provided with the inclined rear wall 8 conforming to the angle of the end 3 of the tongue 2.

HAROLD P. TIPPETT.
